UNITED STATES PATENT OFFICE

CHARLES A. CHANNELL, OF CHICAGO, ILLINOIS, ASSIGNOR TO O-CEDAR CORP'N., OF CHICAGO, ILLINOIS

AUTOMATIC MOP-PAD-MAKING MACHINE

Application filed August 18, 1924. Serial No. 732,657.

This invention relates to the manufacture of mop heads.

One of the principal objects of the invention is to provide means for producing bundles 5 of yarn of the requisite length and number for a mop head.

Another object of the invention is to provide means for automatically measuring, binding and cutting the yarn.

10 Other and further important objects of this invention will be apparent from the disclosures in the accompanying specification and drawings.

The invention (in a preferred form) is illustrated in the drawings and hereinafter more fully described.

On the drawings:

Figure 1 is a diagrammatic plan view of the machine as a whole.

20 Figure 2 is a side elevation of the same.

Figure 3 is an end view of the machine partly in section showing certain steps in the operation.

Figure 4 is a section on the line 4—4 of 25 Figure 3.

Figure 5 is a detail view showing the tape supply rolls and showing the operation of applying the tape to the yarn.

Figure 6 is a plan view of the central portion of the machine.

Figure 7 is a section on the line 7—7 of 30 Figure 6.

Figure 8 is a side elevation of the central portion of the machine.

35 Figure 9 is a side elevational detail showing the tape cutting mechanism.

Figure 10 is a section on the line 10—10 of 40 Figure 2.

Figure 11 is a fragmental view partially in section, showing certain details of construction.

Figure 12 is a diagrammatic view showing the operation.

As shown on the drawings:

45 The machine comprises a bobbin-head 15 revolvably mounted in a frame 16. This bobbin-head has a hollow center through which pass two pairs of endless cables 17. These cables are supported by a series of guide pulleys 18 and driving pulleys 19. The bobbin-

head revolving around these cables wraps yarn therearound and the coiled yarn so formed is carried by the cables between two tape rolls 20 and 21. These rolls feed tape 22 onto each side of the coils of yarn and the 55 whole passes over the platform 23 of a sewing machine 24 which sews the two tapes together with the yarn therebetween. The coils of yarn then pass over a revolving tape cutter 25 which is mounted on a carriage having an 60 elliptical movement lengthwise of the machine such that when the carriage is in the upper part of its movement it is travelling in the same direction and at substantially the same speed as the cables. At this time the 65 cutter 25 is raised high enough to sever both tapes. The cutter then drops and returns to its original position to sever the tapes at another point.

The next step is to sever the yarn adjacent 70 the ends of the loops. For this purpose horizontal revolving cutters 26 are provided which enter the space between each pair of cables 17 as shown more particularly in Figures 1, 2, 10 and 11. The mop sections 75 are then free to drop from the cables 17 onto a belt conveyor 27 arranged therebeneath.

As best shown in Figures 3 and 4 the bobbin-head 15 comprises two drum heads 28 having driving gears 29 attached thereto for engagement with gears 30 upon the main driving shaft 31. On each drum head is a flange 32 between which flanges pass shafts 33 on which bobbins 34 are rotatably mounted. These bobbins carry the yarn which goes to form the 85 mop head.

The bobbin-head revolving about the cables 17 coils the yarn about the latter and these coils are then carried between the tape wheels 20 and 21. As best shown in Figure 5 these 90 tape wheels are rotatably supported by a pair of uprights 35 having slots therein for the reception of the axle pins of the wheels. The tapes feed from the two rolls between a pair of rollers 87, positioned against the upper and 95 under sides of the yarn coils, respectively.

The coils with tape arranged beneath and above pass over a table 23 and under the sewing machine 24 driven from the shaft 31 by gears 36, 37, shaft 38, gears 39, 40 and 100

shaft 41 where the tapes are stitched together thus fastening the yarn to the tapes.

The cutter 25 as best shown in Figures 6 to 9, inclusive, consists of a circular disc driven through suitable gearing 42 by an electric motor 43. This motor is mounted on a platform 44 pivotally connected at one end at 45 to sleeves 46 which slide upon a pair of guide rods 47 carried by the main frame. Adjacent the point 45 are two lugs 48 depending from the platform 44 for pivotal engagement with a link 49. The other end of the link 49 is attached to a second link 50 which in turn is attached at 51 to the connecting rod 52 of an eccentric sheave 53 operated by an eccentric on a shaft 54. This shaft is rotated from a shaft 84 by worm wheel 55 and worm 56; this shaft 84 being in turn driven from the main driving shaft 31 by gears 85 and 86. By means of this eccentric and the link connections referred to the carriage 44 which carries the cutter 25 is oscillated to and fro.

To provide means for adjusting the range and speed of oscillation of the carriage 44 the lower end of the link 50 passes through a block 57 pivotally mounted in a block 58 slidably arranged on a pair of guide rods 59. The block 58 may be clamped on the rods 59 in any desired position and similarly the link 50 may be clamped in adjusted position within the block 57.

In addition to moving the cutter to and fro, it is also raised and lowered to bring it into and out of engagement with the tapes to be cut. The path of movement is therefore roughly elliptical with the cutter rising, moving forward at the same speed as the tapes on the upper part of the path, then dropping and returning. For raising and lowering the cutter, a downwardly projecting arm 60 is arranged on the carriage 44. The lower end of this arm is forked and straddles a frame 62 vertically slidable on a pair of guides 63. Between the forked ends of the arm 60 is a roller 61 adapted to travel in a slot 64 in the upper part of the frame 62. This allows the carriage 44 to oscillate freely to and fro. The frame 62 and the cutter end of the carriage 44 are oscillated up and down by an eccentric 65 on the shaft 54 connected to the frame 62 by sheave 66 and rod 67 (Figure 9). The carriage 44 pivots about the point 45 during this up and down oscillatory motion.

The cutter 25 serves the tapes at the required intervals and the next operation consists in cutting the coils of yarn at their ends.

This is accomplished by circular cutters 26 (shown in Figures 10 and 11) which are supported by brackets 68 and driven by gears 69 and 70 from a shaft 71. This shaft is driven from a cross shaft 72 by grooved pulleys 73, 74 and belt 75.

As the ends of the coils are cut the sections

drop onto a conveyor belt 27 which passes around a pulley 76 on the shaft 72.

This shaft 72 is driven from a shaft 77 by means of a chain and sprocket wheels 78, 79. On the shaft 77 is arranged a worm wheel 80 engaged by a worm 81 on the main driving shaft 31.

The shaft 77 also operates through gears 82 and 83 the driving pulleys 19 for the cables 17.

The operation of the mop machine is shown diagrammatically in stages by Figures 3, 5 and 12. The yarn is wound by the bobbins around the four central strands of the cables 17, the movements of the bobbins and cables being synchronized to give closely and evenly wound coils. As the coils of yarn pass between the tape feed rollers 87, tapes 22 are laid against the upper and lower sides of the coils. The tape next passes over a table 23 and under the foot of a sewing machine 24, which sews the two tapes together with the yarn coils between. The tapes are next severed by the rotary cutter 25, as shown at 88 on Figure 12, and then the yarn is cut at the 90 looped ends 89 of the coils by a pair of stationary cutters 26, positioned on each side of the yarn coils between the upper and lower strands of the cables 17. The length of mop, or swatch, when severed from the cables 17, falls down on a belt conveyor 27, traveling at the same speed as the cables. This swatch is now ready to be formed into a mop head and attached to a mop handle in any suitable manner.

I am aware that numerous details of construction may be varied through a wide range without departing from the principles of this invention, and I therefore do not purpose limiting the patent granted otherwise than 105 necessitated by the prior art.

I claim as my invention:

1. A mop making machine comprising a revolving bobbin-head, two pairs of cables passing through the center of said bobbin-head and movable synchronously therewith, means for applying tape to each side of the coils of yarn produced by the rotation of said bobbin-head around said cables, means for sewing said tapes together with the yarn therbetween, means for cutting the sewn tape into lengths, and means for severing the coils between each pair of cables.

2. A mop making machine comprising a revolving bobbin-head, two pairs of cables passing through the center of said bobbin-head and movable synchronously therewith, means for applying tape to each side of the coils of yarn produced by the rotation of said bobbin-head around said cables, means for sewing said tapes together with the yarn therebetween, a rotary cutter for severing the sewn tapes at intervals, and means for severing the coils between each pair of cables.

3. A mop making machine comprising

means for winding a series of coils of yarn, means for sewing their central portions together between two tapes, a rotary cutter, means for moving said coils over said cutter, 5 and means for moving said cutter in an elliptical path to sever said tapes at predetermined intervals, said cutter in the upper part of its path travelling at the same speed as the tape.

4. In a mop making machine, the combination 10 with two pairs of spaced moving cables, of a plurality of bobbins revolving about said cables and winding loops of yarn thereabout, means for applying tape on each side of said loops, means for sewing said tapes together, 15 means for cutting said tapes at intervals, and means for cutting the looped ends of said yarn between each pair of cables.

5. In a mop making machine, the combination 20 with a plurality of spaced moving cables, of a plurality of bobbins winding loops of yarn about said cables, means for applying tapes to said loops with the yarn therebetween, means for binding said tapes together, 25 means for cutting said tapes at intervals, and means for cutting the looped ends of said coils of yarn.

6. In a mop making machine, the combination 30 with two pairs of traveling cables, of a hollow revoluble bobbin head surrounding said cables, a plurality of bobbins carried by said bobbin head for winding coils of yarn about said cables, means for applying strips of tape to said coils with the yarn therebetween, means for sewing said strips together, 35 means for cutting said strips into equal lengths, and means for severing the looped ends of said coils of yarn.

7. A mop making machine comprising two 40 pairs of endless traveling cables, a hollow revoluble bobbin head enclosing four strands of said cables, a plurality of yarn carrying bobbins mounted on said bobbin head for winding coils of yarn about said cable strands, means for sewing tapes together 45 with said yarn therebetween, a rotary cutter adapted to cut said tapes at predetermined intervals, and means for severing said coils of yarn at their looped ends.

8. A mop making machine comprising a 50 conveying means, means for coiling yarn about said conveying means, means for binding said coils of yarn together, means for cutting said binding at definite intervals, and means for cutting said coils of yarn.

55 9. In apparatus for making mops, two pairs of endless traveling cables on which yarn is wound and bound in strips, in combination with a traveling rotary cutter mounted between said pairs of cables and adapted 60 to travel with said cables during a part of its path to cut said strips into predetermined lengths.

10. In apparatus for making mops, two 65 pairs of endless traveling cables on which yarn is wound, in combination with a pair of

tape feed rolls for including said yarn between two tapes, and means for sewing said tapes together.

11. In apparatus for making mops, two 70 pairs of traveling endless cables on which yarn is wound, in combination with means for sewing two tapes together with said yarn therebetween, traveling cutting means for severing said tapes at intervals, and stationary cutting means for severing said yarn at its looped ends.

12. A mop making machine comprising a traveling endless mechanism about which 75 yarn is wound, a sewing mechanism for binding said yarn together, a traveling cutting mechanism for separating said yarn into bound strips, a stationary cutting mechanism for cutting said yarn at its looped ends, and means for driving the various mechanisms from a single driving shaft.

80 13. In apparatus for making mops, a support, a revolving bobbin mechanism mounted on said support, a sewing mechanism, a traveling cutting mechanism, a stationary cutting mechanism, a common driving shaft geared 85 to said mechanism, in combination with two pairs of cables driven by said shaft upon which yarn is wound by said bobbin mechanism and by which the yarn is carried past said other mechanisms to be made into mop 90 lengths.

14. In apparatus for making mops, endless 95 traveling conveyors on which yarn is wound and bound in strips, in combination with cutting mechanism adapted to travel with said 100 conveyors during a part of its path for cutting said strips into predetermined lengths.

15. A mop pad making machine comprising 105 an endless traveling mechanism, means for winding coils of yarn thereabout, means for applying band material to said coils intermediate the ends of the coils with the yarn therebetween, and a sewing mechanism associated therewith and adapted to bind said band material together.

110 16. A mop making machine comprising a revolving hollow mechanism carrying a plurality of rotatably mounted bobbins of yarn, a plurality of endless traveling cables passing through and around said mechanism, upon which the yarn is adapted to be coiled, rolls of tape rotatably mounted above and below the yarn so coiled, a sewing mechanism adapted to bind said tapes together with the yarn therebetween, a rotary knife traveling 115 through an elliptical path and adapted to sever said sewn tapes at predetermined intervals, stationary knives positioned between adjacent strands of said cables adapted to sever the looped ends of said coils of yarn, 120 and a traveling conveyor positioned below said cables to receive the severed strips.

17. In a mop pad making machine, a hollow 125 bobbin head, a plurality of bobbins of yarn rotatably mounted thereon and axially 130

parallel thereto, a plurality of endless spaced cables passing through said bobbin head, and means for revolving said bobbins to wind said yarn around said traveling cables.

5 18. In a mop pad making machine, a hollow bobbin head, a plurality of bobbins of yarn rotatably mounted thereon and axially parallel thereto, a plurality of endless spaced cables passing through said bobbin head, 10 means for revolving said bobbins to wind said yarn around said traveling cables, a pair of tape rolls, one mounted above and the other below said traveling cables, and means for securing tapes carried by said rolls to said coils of yarn with the yarn therebetween.

15 19. In a mop pad making machine, a hollow bobbin head, a plurality of bobbins of yarn rotatably mounted thereon and axially parallel thereto, a plurality of endless spaced cables passing through said bobbin head, 20 means for revolving said bobbins to wind said yarn around said traveling cables, a pair of tape rolls, one mounted above and the other below said traveling cables, means for securing tapes carried by said rolls to said coils of 25 yarn with the yarn therebetween, a rotary knife pivotally mounted below said traveling cables, and means for moving said rotary knife in a substantially elliptical path and 30 into contact with said binding tapes to sever the same.

20 20. In a mop pad making machine, a hollow bobbin head, a plurality of bobbins of yarn rotatably mounted thereon and axially 25 parallel thereto, a plurality of endless spaced cables passing through said bobbin head, means for revolving said bobbins to wind said 30 yarn around said traveling cables, a pair of tape rolls, one mounted above and the other 35 below said traveling cables, means for securing 40 tapes carried by said rolls to said coils of yarn with the yarn therebetween, a rotary knife pivotally mounted below said traveling cables, means for moving said rotary knife 45 in a substantially elliptical path and into contact with said binding tapes to sever the same, and other rotary knives horizontally 50 disposed between adjacent upper and lower strands of the cables for severing the yarn to form swatches.

21 21. In a mop pad making machine, a hollow bobbin head, a plurality of bobbins of yarn rotatably mounted thereon and axially parallel thereto, a plurality of endless spaced cables passing through said bobbin head, 25 means for revolving said bobbins to wind said yarn around said traveling cables, a pair of tape rolls, one mounted above and the other below said traveling cables, means for securing 30 tapes carried by said rolls to said coils of yarn with the yarn therebetween, a rotary knife pivotally mounted below said traveling cables, means for moving said rotary knife 35 in a substantially elliptical path and into 40 contact with said binding tapes to sever the 45 same, other rotary knives horizontally 50 disposed between adjacent upper and lower strands of the cables for severing the yarn to form swatches, and conveying means underneath said traveling cables for catching the 55 swatches.

70 22. In a mop pad making machine, means for forming a continuous coil of yarn, means for binding said coil into a continuous strip and means for severing said strip at predetermined intervals, said last mentioned means comprising a rotary cutter and eccentric driving means pivotally associated therewith for moving said cutter in a substantially elliptical path.

75 23. In a mop pad making machine, a main driving shaft, a plurality of pulleys driven therefrom, endless cables driven by said pulleys on which a continuous coil of yarn is adapted to be formed, a rotary cutter mounted below said cables, a transverse shaft driven from said main shaft, means eccentrically driven from said transverse shaft and pivotally connected to said rotary cutter for horizontally reciprocating said cutter, and other means eccentrically driven from said transverse shaft and connected to said cutter to effect vertical movement of said cutter into contact with said continuous coil of yarn to sever the same at predetermined intervals.

80 24. The combination in a mop pad making machine, of a traveling endless mechanism, means for winding and binding coils of yarn together upon said mechanism in a continuous strip, and a cutter adapted to sever said strip into predetermined lengths.

In testimony whereof I have hereunto subscribed my name.

CHARLES A. CHANNELL.
